UNITED STATES PATENT OFFICE.

EUGENE ROBERTS AND ANGUS H. GIBSON, OF LEHI, UTAH, ASSIGNORS TO SUGAR CENTRIFUGAL DISCHARGER COMPANY, OF SALT LAKE CITY, UTAH, A CORPORATION OF UTAH.

BASKET FOR CENTRIFUGAL MACHINES.

1,108,098.

Specification of Letters Patent. Patented Aug. 18, 1914.

Application filed February 13, 1913. Serial No. 748,114.

To all whom it may concern:

Be it known that we, EUGENE ROBERTS and ANGUS H. GIBSON, citizens of the United States, and residents of Lehi, county of 5 Lehi, State of Utah, have invented certain new and useful Improvements in Baskets for Centrifugal Machines, of which the following is a specification.

This invention relates to the basket-screen 10 of a centrifugal machine and is intended to provide an efficient and satisfactory mode of fastening the ends of the foraminous plate or screen which forms the peripheral wall of the basket.

15 It is the common practice to cut the plates used for such screens of sufficient length so that when bent into cylindrical form and inserted in the basket frame, the two ends overlap each other, while being free to expand or slip over each other in a circumferential direction. This arrangement, however, results in an accumulation of sugar in the crack between the two overlapped ends, and as the ends are free to spread apart laterally, a considerable mass of unpurified sugar may accumulate in this space and cause the inner end of the screen or wall to project inwardly so as to seriously interfere 25 with the plow used for discharging or scraping away the sugar from the inside when the basket is discharged of its load.

This invention consists in so constructing the screen that the overlapped ends are interlocked so as to prevent the accumulation 30 of sugar and the spreading apart of the overlapped ends while allowing the two ends to slip slightly over each other in a circumferential direction as the screen stretches or expands in actual service.

40 To this end the invention comprises a foraminous sheet or screen, preferably of metal, one of whose ends is slotted from the end edge inwardly to form a series of tongues, the other end being provided with a series 45 of narrow oblong perforations extending in a direction parallel to the adjacent edge, and so disposed as to receive and retain a portion of the tongues, while the other tongues, preferably each alternate tongue, is passed out- 50 side of the end provided with retaining slots or perforations.

In the drawings we have illustrated the preferred form of embodying the principles of this invention.

55 Figure 1 is a plan view of the flat tongue

of foraminous material before it is bent into cylindrical form for insertion into the basket; Fig. 2 is a perspective view of the screen or wall in operative position; and Fig. 3 is a vertical plan or edge view showing the position of the interlocking tongues.

In the practice of the invention according to the form illustrated in the drawings we take a sheet of suitable material whose width corresponds to the depth of the circumferential wall of the basket and bend back one end edge on itself along the line of a series of transverse narrow apertures a' which extend parallel to the adjacent edge a short distance therefrom.

The opposite end of the foraminous sheet is slotted transversely inward from the edge so as to form a series of tongues b , each alternate tongue being formed to align with a corresponding aperture a' in the opposite end of the sheet a , the sheet or blank is then bent or curled into cylindrical form with the flap or end a^2 bent back outside of the sheet along the line of the apertures a' . The opposite ends are then brought together and the tongues b are pushed through the apertures a' , the other series of tongues b' , or preferably each alternate tongue, passes outside of the turned-back flap or end portion a^2 , so that the perforated end is held between the tongues b , b' but in such a manner that the sheet under the action of centrifugal force and the heavy wall of sugar built up on the inside of the screen, may be free to expand slightly but without any lateral separation of the interlocked ends. With this arrangement it is not possible to accumulate any appreciable amount of sugar or other solid material between the overlapped ends, nor is it possible for the overlapped ends to spread apart so as to interfere with the satisfactory operation of a discharger plow.

The basket c may be of any usual or suitable construction, while we prefer to form the tongues b and the overlapping members of the opposite edge which form so to speak retaining straps, integrally from the sheet of metal itself. It will, of course, be understood that such details are not essential, the important requisite being that the free ends of the screen should be interlocked to prevent lateral separation.

What we claim is:

1. A screen for a centrifugal basket com-

prising a foraminous sheet, one of whose ends is provided with a series of elongated perforations adjacent to and substantially parallel with the edge of said end, the other 5 end being slit transversely to its edge inwardly to form a series of tongues, a portion of which are disposed to pass through the said elongated perforations to form an interlocking engagement between the two ends to 10 prevent lateral separation of the ends, substantially as described.

2. A screen for a centrifugal basket comprising a foraminous sheet of flexible material, one of whose ends is folded back exteriorly and provided with a series of interrupted elongated perforations at the line of 15 said fold, the other end of said sheet being slotted inwardly from its edge to form a series of circumferentially extending tongues 20 some of which are disposed to aline with and pass through said perforations when the two ends are brought together, the remaining tongues being passed outside of the opposite end whereby the two ends are interlocked 25 against lateral separation while allowing circumferential expansion, substantially as described.

3. A basket for a centrifugal machine embracing a frame, a removable peripheral 30 wall or screen whose ends are overlapped, one of said ends being provided with a series of vertical elongated perforations adjacent to its edge, the other end being slotted in the direction of the circumference for a short 35 distance to form a series of contiguous tongues, each alternate tongue being passed through a corresponding perforation in the opposite end whereby the two ends are interlocked against lateral separation, substantially 40 as described.

4. A screen for a centrifugal basket comprising a foraminous sheet bent into approximately circular contour with its free ends held against lateral separation by a

series of overlapped interwoven tongues and 45 strap members while permitting circumferential play of the tongues in relation to the strap members, substantially as described.

5. A screen for a centrifugal basket embracing a foraminous sheet bent into approximately circular form, the ends of said sheet being provided respectively with a series of projecting tongues and a corresponding series of receiving slots by which the ends may be overlapped and interwoven 55 to prevent their lateral separation while permitting play of the tongues in the slots in a circumferential direction, substantially as described.

6. A cylindrical screen for a sugar centrifugal machine, comprising a foraminous bent sheet having one longitudinal edge bent outwardly upon itself to provide a flap disposed wholly exteriorly of said sheet and lying flat thereon, said sheet being provided 65 at the bending point with spaced longitudinal slots, said sheet having its opposite longitudinal edge transversely slotted at spaced intervals to provide inner and outer sets of outwardly offset tongues, the inner set of 70 outwardly offset tongues fitting within the slots whereby the inner wall of the double walled edge of the sheet is substantially flush with the inner wall of the opposite edge of said sheet, and the outer set of tongues engaging the exterior of said flap, the two sets of tongues, together with the slotted double-walled edge of the sheet effecting a circumferentially yieldable joint which is incapable 75 of having its parts laterally separated. 80

In witness whereof, we have subscribed the above specification.
